WO 94/17716 8/1994 WIPO.

Primary Examiner—Ruth McInroy*Attorney, Agent, or Firm*—Varnum, Riddering, Schmidt & Howlett LLP[57] **CLAIM**

The ornamental design for a base of a cleaning machine, as shown and described.

DESCRIPTION

FIG. 1 is a front, perspective view of the base of a cleaning machine showing my new design;

FIG. 2 is a front elevational view thereof;

FIG. 3 is a rear elevational view thereof;

FIG. 4 is a left side-elevational view thereof, the right side-elevational view being a mirror image thereof;

FIG. 5 is a top plan view thereof; and,

FIG. 6 is a bottom plan view thereof.

The broken line showing of the upper housing and handle of a cleaning machine in FIGS. 1-4 is for illustrative purposes only and forms no part of the claimed design.
